UNITED STATES PATENT OFFICE.

VIRGIL H. MILLS AND JOHN H. T. MILLS, OF HUBBARD, TEXAS.

OIL BURNER.

1,409,390.

Specification of Letters Patent. Patented Mar. 14, 1922.

Application filed January 14, 1920. Serial No. 351,374.

To all whom it may concern:

Be it known that we, VIRGIL H. MILLS and JOHN H. T. MILLS, citizens of the United States, residing at Hubbard, in the county of Hill and State of Texas, have invented certain new and useful Improvements in Oil Burners, of which the following is a specification.

This invention relates to an improved apparatus for and method of consuming liquid fuel and particularly heavy oils or hydrocarbons which have heretofore been burned only with great difficulty. There are various heavy oils or hydrocarbons which may be obtained at an extremely low cost, such for example as the heavy products known as fuel oil, residuum, and the like but which cannot be successfully consumed in an ordinary liquid fuel burner although we have found that they constitute excellent fuels when burned in accordance with the method of the present invention.

It is, therefore, an object of the present invention to provide means whereby fuel of this nature may be successfully consumed in an economical and inexpensive manner.

Another object of the invention is to provide means for vaporizing the liquid fuel or converting the same into a gas or mixture of gases and for simultaneously igniting the gases at their point of generation so that the gases are consumed while in their nascent state and are thus prevented from cooling or condensing, prior to ignition, to such extent as to interfere with their complete combustion.

Another object of the invention is to provide thermal means for instantaneously cracking or breaking up the particles of liquid fuel supplied thereto and for burning the same into a gas or mixture of gases and to effect combustion of these gases at the instant they are generated.

Another object of the invention is to provide in an apparatus constructed to consume liquid fuel in the manner above referred to, an arrangement whereby air, for the purpose of supporting combustion, may be most effectively supplied during the operation of the apparatus and in such a manner as to insure of complete combustion of the gaseous fuel under the most favorable conditions.

In the accompanying drawings:

Figure 1 is a perspective view of a heating stove equipped with the apparatus of the present invention;

Fig. 2 is a vertical front to rear sectional view through a portion of the apparatus;

Fig. 3 is a detail vertical transverse sectional view on the line 3—3 of Fig. 2;

Fig. 4 is a perspective view of a portion of the apparatus;

Fig. 5 is a view in elevation illustrating the valve for regulating the fuel supply;

Fig. 6 is a view partly in plan and partly in horizontal section illustrating a modified embodiment of the invention;

Fig. 7 is a vertical longitudinal sectional view through the structure shown in Fig. 6;

Fig. 8 is a plan view of a member of the structure shown in Fig. 7.

The principles of the invention may find embodiment in heating stoves of various sizes, cooking stoves, hot air and boiler furnaces, and in fact in practically any type of stove or furnace.

However, the description which is to follow deals chiefly with the invention as applied to domestic heating and cooking stoves, its application on a larger scale being set forth in our copending application filed January 14, 1920, Serial No. 351,375. On the other hand it is to be understood that the drawings are to be considered as merely illustrative of possible embodiments of the invention and that the principles of the invention may find various other embodiments and that consequently various modifications may be made in the apparatus employed without in any way departing from the spirit of the invention.

In the drawings the invention is illustrated as employed in connection with a heating stove of the drum type and of this stove, the drum or body is indicated by the numeral 1, the flue by the numeral 2, and the usual damper in the flue by the numeral 3. The apparatus of the present invention includes a combined generating and combustion chamber which indicated in general by the numeral 4, is in the present instance mounted upon the exterior of the stove drum 1 although it may be found desirable to mount this chamber directly within the drum or to so construct the stove that the

chamber will constitute a part of the drum. However, in the illustrated structure, the combustion chamber is as stated, mounted upon the exterior of the drum 1 and its interior is in communication with the interior of the drum at the front of the latter by way of an opening 5 formed in the forward wall of the said drum, which wall constitutes the rear wall of the chamber 4. This chamber further includes a bottom wall 6 and a top 7 which latter is formed with an opening 8 of any desired size and shape normally closed by a lid 9 which may be provided, if desired, with a flange 10 to seat within the opening 8. Any means suitable for the purpose may be provided for conveniently removing and replacing this lid and, for a purpose to be presently explained, the lid is formed preferably centrally with an opening 11. A baffle plate 12 is secured at its upper end to the plate 9 at the rear side of the opening 11 and this plate projects downwardly in forwardly inclined position through the opening 11 and beneath the lid 9 and into the said chamber 4. It is preferable that the plate 12 be gradually narrowed in the direction of its lower end as clearly shown in Figs. 3 and 4 of the drawings. A deflector plate 13 is secured at its upper end to the lid 9 at the forward side of the opening 11 or, in other words, directly opposite the plate 12 and likewise projects downwardly through the said opening 11 and beneath the lid 9 and into the chamber 4. This deflector plate may likewise be gradually narrowed in the direction of its lower end and the said plate preferably depends substantially vertically when the lid is in place. It is also to be noted and particularly by reference to Figs. 2 and 4 of the drawings that the lower end of the plates 12 and 13 are suitably spaced apart and that the space at the opposite sides of the plates 12 and 13 is left open. The top 7 is provided immediately beneath the opening 8 with means for supporting a flash pan and this means preferably comprises relatively deep side walls 14 which depend from the under side of the top 7 at the opposite ends of the opening 8 and are provided with inwardly projecting horizontally disposed supporting flanges 15 which are preferably inclined downwardly and rearwardly to a slight degree as in Fig. 2 of the drawings. Likewise the top 7 is provided, at the rear side of the opening 8, with a depending flange or apron 16 having one or more lugs 17 projecting downwardly from its lower end, this flange or apron extending between the walls 14 as clearly shown in Fig. 3 and the lower edge thereof being located considerably above the plane occupied by the flanges 15. The flash pan above referred to is indicated in general by the numeral 18 and the said pan com-

prises a bottom 19, sides 20, and a rear wall 21, the pan being open at its front and top and having its bottom 19 inclined downwardly and rearwardly toward the wall 21 so that the pan is gradually increased in depth to a slight degree from its forward to its rear side. The pan is of a shape and size to be fitted between the side walls 14 with its bottom resting upon the flanges 15 as clearly shown in Figs. 2 and 3 of the drawings and with its rear wall 21 abutting against the lower ends of the lugs 17 but with its upper edge spaced below the lower edge of the flange 16 so as to provide a draft passage 22.

Fuel is to be fed to the flash pan by means which will now be described. The numeral 23 indicates a drip nozzle which is fitted through the lid 9 preferably directly rearwardly of the baffle plate 12 with its lower end positioned to discharge into the flash pan 18 near the rear end thereof, and this nozzle is provided at its upper end with a funnel shaped mouth 24 into which the liquid fuel is to be discharged from the lower end of a pipe 25 held by a bracket 26 in position suitably spaced above the mouth 24 of the drip nozzle to permit of the feed of the fuel to the nozzle being readily observed. The pipe 25 leads downwardly from a supply tank or reservoir 27 in which the liquid fuel is contained, and a valve 28 is interposed in the pipe 25 between the said reservoir 27 and the discharge end of the pipe and is provided with a head 29 by means of which the valve may be rotatably adjusted to regulate the supply of fuel. An adjustable abutment screw 30 is threaded through an extension 31 of the head 29 and is designed to bear at its end against the lower end of the valve casing or any other suitably located abutment portion or element and it will be understood that by adjusting this screw, the extent to which the valve may be opened may be limited.

The foregoing description relates particularly to that form of the invention shown in Figs. 1 to 5 inclusive and in the operation of this form of the invention, an initial quantity of fuel is ignited in the pan 18 and when the pan has become suitably heated, the valve 28 is opened so as to permit the fuel to flow very gradually from the reservoir 27 to the nozzle 23 from the lower end of which it is discharged either a drop at a time or in a very small stream, into the said pan. The draft through the flue 2 will cause air to be drawn in through the opening 11 and as the air currents flow downwardly through this opening, they will sweep over the top of the pan and supply oxygen for the combustion of the gas which is generated from the oil. When the apparatus is in operation, the liquid fuel will be instantaneously vaporized upon striking the intensely heated flash

pan or probably even before reaching the said pan and at the moment the liquid fuel is converted into gas, the gas is ignited and is completely consumed. The combustion of 5 the gas will create an intense heat which will play not only against the upper but also against the under side of the bottom of the pan so that there will be no likelihood whatsoever of the fuel condensing or accumulat- 10 ing or caking in the pan. It will be understood, of course, that the air currents and flames will sweep over the forward end of the pan as well as over the rear wall 21 thereof through the space 22, and the burning 15 gases will be carried by the draft, from the chamber 4 through the opening 5 and into the drum 1, the products of combustion passing out through the flue 2 and creating the said draft. It will be understood that 20 the baffle plate 12 serves effectually to prevent the inrushing draft of air from deflecting the fuel discharged from the drip nozzle 23 or chilling this fuel before it is converted into gas. It will also be evident that the 25 deflector plate 13 prevents the inrushing currents of air sweeping directly forwardly over the upper surface of the bottom of the flash pan which would have the result of blowing the fuel out of the pan and inter- 30 fering with its conversion into gas. On the other hand the air currents are admitted into the generating and combustion chamber through the opening 11 in such a manner that they will completely envelop the ig- 35 nited gases and thus insure of perfect and complete combustion thereof. It may be stated in this connection that we have found that if the bottom of the flash pan is heated only at its upper surface or only at its lower 40 surface, the desired results cannot be obtained and it is for this reason chiefly that the pan is so arranged and supported that the heat from the burning gases is caused to play both upon the upper and under surfaces 45 of the said bottom. It is again stated that in the operation of the apparatus the bottom of the pan if not the entire pan will be brought to an intense white heat and conse- 50 quently the liquid fuel discharged into the pan from the drip nozzle will be instantaneously converted into gas and simultaneously with their generation, the gases will be ignited, in the presence of a sufficient volume of air to insure of their complete and 55 instantaneous combustion.

In that form of the invention shown in Figs. 6, 7 and 8 of the drawings, the combustion chamber which in these figures is indicated in general by the numerals 32, in- 60 cludes a bottom 33 and a top or lid 34 which is shown in section in Fig. 7 and in plan in Fig. 8 and which is preferably pivoted at one corner as at 35 to the wall of the combustion chamber so that it may be swung to 65 one side to permit of access to the said cham- ber. The arrangement of the chamber is substantially the same as in the previously described form of the invention but in this latter form the lid 34 is formed with an annular series of openings 36 and with a 70 central fuel opening or passage 37. A tubular standard 38 is mounted within the chamber to upstand from the bottom 33 thereof, and removably fitted into the upper end of this standard is the stem 39 of a supporting 75 spider, the arms of which are indicated by the numeral 40 and radiate from the upper end of the said stem. The flash pan in this form of the invention is indicated by the numeral 41 and the same is preferably shallow and is of a marginal outline correspond- 80 ing substantially to the shape of the series of openings 36. That is to say, if the pan is circular, the openings will be arranged in a circular series or, if the pan is rectangular 85 the openings will be arranged in a rectangular series. Therefore, within the terms of the invention, the pan may be of any mar- ginal contour and the openings will be ar- ranged in a series of corresponding forma- 90 tion. The bottom of the pan 41 is preferably provided with a shallow depression 42 located centrally thereof and immediately be- 95neath the fuel opening 37. Fuel is dis- charged from a supply pipe 43 located above the lid 34 and drips from this pipe through the opening 37 and onto the bottom of the pan 41. The pan being maintained at an intense heat, the fuel will be instantaneously vaporized and converted into gas upon strik- 100 ing the pan and due to the draft created within the drum of the stove, air will be drawn into the combustion chamber through the openings 36 and will be caused to sweep over the periphery of the pan thus supply- 105 ing oxygen for the combustion of the gen- erated gases and completely enveloping these burning gases in a combustion supporting atmosphere. In this form of the invention as in the previously described form, the heat 110 from the burning gases will be transmitted to the upper surface of the pan and also to the under surface thereof. It will be ob- 115 served by reference to Fig. 7 that the open- 120 ings 36 are located above and immediately inwardly of the periphery of the pan and we have found this arrangement to be the one producing the best results. It will be evi- 125 dent at this point that instead of providing the standard 38 and spider comprising the parts 39 and 40, the pan 41 may be support- ed in some other manner and as before pointed out the invention is not restricted to the specific details of structure illustrated in the drawings. By providing the de- 130 pression 42 in the central portion of the bottom of the pan 41, a small quantity of fuel ini- tially discharged into the pan will not scatter but will be concentrated at this point.

In either form of the invention, the flash 130

pan may be readily removed for the purpose of cleaning the same. It will also be understood from the foregoing that in each form of the invention the flash pan is so supported that the air drawn into the combustion chamber may substantially completely envelope the pan and consequently the burning gases and thus provide for complete combustion of said gases.

10 Having thus described the invention, what is claimed as new is:

1. In apparatus of the class described, a combustion chamber having a draft outlet in its lower portion and a draft intake in its upper portion, a baffle and a deflector arranged at opposite sides of the said intake to direct the draft in a downward direction at an angle, a thermal flashing pan disposed

beneath the intake and having an open side in the path of the draft, and means for feeding fuel to the said pan.

2. In apparatus of the class described, a combustion chamber having an outlet in its lower portion and provided in its top with a continuous series of draft intake openings and a fuel inlet opening surrounded by the series of intake openings, and a thermal flashing pan located within the combustion chamber beneath the said top thereof and in the path of the air currents flowing through the intake openings and through the said chamber to the outlet.

In testimony whereof we affix our signatures.

VIRGIL H. MILLS. [L.S.]
JOHN H. T. MILLS. [L.S.]
